UNITED STATES PATENT OFFICE.

HOWARD MORGAN, OF QUINTER, KANSAS.

TELEPHONE RELAY OR REPEATER.

979,986.

Specification of Letters Patent. Patented Dec. 27, 1910.

Application filed May 19, 1909. Serial No. 496,914.

To all whom it may concern:

Be it known that I, HOWARD MORGAN, a citizen of the United States, residing at Quinter, in the county of Gove and State of Kansas, have invented new and useful Improvements in Telephone Relays or Repeaters, of which the following is a specification.

This invention relates to a telephone relay or repeater adapted for use between two lines or circuits or between portions of a grounded or metallic circuit for transmitting vocal or bell ringing impulses from one to the other without a direct connection between them.

The object of the invention is to provide a simple, effective and inexpensive construction of device of this character through which impulses may be equally well sent in both directions, which may be used for the above stated and other purposes, such as for temporarily connecting independent lines, which will intensify the current impulses to enable messages to be sent long distances or over lines having weak current supply, and which is adapted for direct use without a local battery.

The invention consists of the features of construction, combination and arrangement of parts hereinafter fully described and claimed, reference being had to the accompanying drawing showing a sectional elevation of my improved relay as arranged for use.

Referring to the drawing, the relay or repeater comprises a frame or inclosing casing 1 having removable end heads 2 which are preferably flanged to overlap the ends of the casing and are secured in position by adjusting screws 3.

Arranged within the casing are two sets of electromagnets 4 and 5 disposed in opposed relation, and with their pole faces 6 in contact or slightly spaced apart. Each set, which is fixed to the covers 2, bear against insulated base pieces 7, secured by screws 8 to the covers, and to which said magnets are suitably fastened.

On one of the covers 2 are mounted binding posts 9 and 9^a, and on the other cover 2 are mounted similar binding posts 10 and 10^a. To the first named binding posts are attached the transmitting and ground or return wires 11 and 11^a, respectively, of one circuit or telephone line, or a portion of a telephone circuit or line, while connected with the other binding posts 10 and 10^a are

the transmitting and ground or return wires 12 and 12^a, respectively, of another telephone circuit or portion of the same circuit, which sets of wires are respectively coupled through their sets of binding posts with the windings of the respective sets of electromagnets 4 and 5.

In the use of the relay or repeater, such instrument is arranged between two telephone lines or circuits or portions of the same line or circuit, wherever it is desired to overcome weakness of current strength in the line or to transmit messages between separate circuits without directly connecting the wires thereof. Arranged in operative position as described, the device is designed and operates to transmit from one line or circuit to the other line or circuit or portions of the same line or circuit the vocal and ringing impulses transmitted from any telephone instrument in the line and to transmit the same with increased intensity along the line or from one circuit or branch of a circuit to another, whereby disadvantages attendant upon weak current strength in any circuit or directly connecting two independent circuits are effectually avoided.

Assuming that ringing or vocal impulses are being transmitted from an instrument through the conductor 11, it will be understood that the current of the line will pass therefrom through the binding post 9 to and through the electromagnets 4, and thence through the binding post 9 through the conductor 11^a to the ground or source. By this means the electromagnets 4 will be energized and will in turn influence and set up an induced current in the coils of the magnets 5, whereby the impulses will be transmitted through the conductor 12. Assuming on the other hand that vocal or ringing impulses are being transmitted through the conductor 12 from a telephone instrument connected therewith, it will be apparent that the current will pass through the binding post 10 to the magnets 5, and thence to the ground or back to the source through the binding post 10^a and conductor 12^a. As a result, the magnets 5 will be energized and set up an induced current in the magnets 4, transmitting the vocal or ringing impulses to and through the conductor 11.

It will thus be seen that my invention provides a simple and inexpensive construction of relay which will operate to transmit current impulses in either direction, and may be

directly coupled to the conductors of separate lines or portions of the same line for direct transmission and without the necessity of employing an auxiliary or local battery circuit. My invention thus overcomes objections to prior devices of its kind, and is of value in enabling both bell signal impulses and vocal impulses to be directly transmitted, whereby simplicity of construction is secured and the system rendered less liable of getting out of order.

Claim:

The combination with the transmitting and ground or return wires of adjacent circuits or sections of a circuit, of a supporting frame provided with sets of binding posts to which the wires of the respective circuits or

sections of a circuit are connected, a set of magnets carried by said frame and connected with one of said sets of binding posts, and a second set of magnets carried by the frame and connected with the other set of binding posts, said sets of magnets having their pole faces arranged in juxtaposition, whereupon upon the energization of either set of magnets corresponding induced currents will be set up in the other set of magnets, substantially as described.

In testimony whereof I affix my signature in presence of two witnesses.

HOWARD MORGAN.
